Primary Examiner—Brian N. Vinson*Attorney, Agent, or Firm*—Oldham, Oldham & Wilson Co.[57] CLAIM

The ornamental design for a bathroom convenience cabinet, as shown and described.

DESCRIPTION

FIG. 1 is a front elevational view of a bathroom convenience cabinet showing my new design;

FIG. 2 is a rear elevational view thereof;

FIG. 3 is a right side elevational view thereof;

FIG. 4 is a left side elevational view thereof;

FIG. 5 is a top plan view thereof;

FIG. 6 is a bottom plan view thereof;

FIG. 7 is a reduced front elevational view thereof, with the cabinet door shown in an open position; and,

FIG. 8 is a reduced horizontal cross-sectional view thereof, taken along line 8—8 of FIG. 7.

The broken-line disclosure of various bathroom supplies in the views is for illustrative purposes only and forms no part of the claimed design.
